UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

PRINTING MECHANISM.

1,261,956.

Specification of Letters Patent.

Patented Apr. 9, 1918.

Application filed June 24, 1914. Serial No. 847,112.

To all whom it may concern:

Be it known that I, EDWARD J. VON PEIN, a citizen of the United States, residing at Dayton, in the county of Montgomery and 5 State of Ohio, have invented certain new and useful Improvements in Printing Mechanism, of which I declare the following to be a full, clear, and exact description.

This invention relates to improvements in 10 accounting machines, and has particular reference to improvements in the printing mechanism thereof.

A main object of the invention is to provide a device which may be embodied in 15 cash registers and other forms of accounting machines having printing mechanisms whereby, in addition to performing their usual functions, such machines may be made to serve satisfactorily as check printers or 20 check protectors.

A number of different styles of such machines are now in general use, arranged to print amounts on inserted checks, drafts and similar papers, one object being to enforce 25 a record of the amounts in the record retaining devices of the machines as an incident to the printing operation, and another to make it more difficult to raise the amount for which the paper is drawn. This arrangement gives satisfactory protection as far as 30 the compulsory record is concerned, but does not give a full measure of protection in the way of preventing fraudulent alterations of the amounts printed, as said amounts are 35 usually printed in figures, and it requires the addition or alteration of but one or two figures to make such a fraudulent change. It is apparent, of course, that increasing the number of characters which must be altered 40 will increase the difficulty of making such alterations without detection. This can probably be best accomplished by printing the full words representing the different denominational values, instead of representing 45 the values by figures and decimal points.

However, the mere substitution of word printing type for the usual figure or digit type, does not accomplish all that is necessary to produce a satisfactory mechanism. 50 This is because of the construction of the type carriers and their operating mecha-

nism. The type carrier in general use is arranged to print the digits 0 to 9 for a particular denominational order, or ten digits in all and are generally each operated by 55 differential mechanism controlled by a series of keys and limited to 9 or 10 steps of movement, the arrangement being such that the digit representing the key operated will be positioned at the printing line. If word 60 printing type are substituted for the digit type, the protection is, as before stated, increased materially, but there remains to be overcome the obstacle which has, as far as applicant is aware, prevented prior satis- 65 factory application of word printing type carriers to machines of the differential type just mentioned. This obstacle is presented by the fact that the mere substitution of words for digits does not provide for satis- 70 factorily printing the words representing amounts between 10 and 20, *i. e.* "eleven," "twelve" and the teens "thirteen" to "nineteen" inclusive in both the dollars and cents orders. For example, such type would 75 print from the units and tens of cents carriers the words "Ten" "Five cents", instead of the decimal points and digits .15, while, of course, there should be printed "Fifteen cents." This invention consists mainly in 80 the means by which the obstacle just mentioned is overcome.

In the accompanying drawings, the invention is shown applied to a cash register such as is fully illustrated and described in 85 United States Letters Patent No. 703,639, granted July 1, 1902 and No. 754,049, granted March 8, 1904, to Thomas Carroll. However, as has already been stated, the invention is not limited in its application to 90 any one particular kind of machine, but is capable of application in various modifications to accounting machines in general. In fact, as will appear clearly after the construction is fully understood, the idea is 95 capable of embodiment in structurally separate check printing or protecting devices, such as the ordinary hand operated stamps now in general use in banks and business houses.

It will also be apparent after the invention is clearly understood, that while the

improvement is shown as applied to rotatable type carriers, it is not limited to such an embodiment, but can be applied with equal facility to indicators or similar devices which it may be desirable to first differentially position and then give an additional degree of movement as an incident to further operation of the mechanism comprising such devices.

10 With the above and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Of the said drawings:

20 Figure 1 is a transverse vertical section taken at the right of one of the higher order key banks.

Fig. 2 is a transverse vertical section taken on the line AA (Fig. 5) and showing the printing mechanism and certain features of the driving mechanism.

Fig. 3 is a chart showing the arrangement of the type on the type carriers.

Fig. 4 is a group of details showing the type carriers in right elevation.

Fig. 5 is a plan view of the printing mechanism. Certain of the parts have been omitted and others broken away, the object being to show to the best advantage the parts directly involved in the invention.

Fig. 6 shows in section certain features of the control for the type carrier operating mechanism.

Fig. 7 is a detail of that part of the controlling mechanism shown in Fig. 6 which is designed to control the units and tens of cents type carrier operating mechanism.

Fig. 8 shows in detail the construction of one of the lower order type carriers, the type being omitted from the periphery for the sake of clearness.

Fig. 9 shows how the amounts are printed on checks by the improved machine.

The machine of the Carroll Patent No. 50 754,049, to which the invention is shown applied, is one of the ones mentioned above as having ten division type carriers and key controlled differential mechanism for operating them. In applying the invention thereto, type carriers of approximately twice the circumference shown therein have been used and the width of the carriers has also been increased. Raised word printing type are arranged about the periphery of the carriers and are of about the same height as the digit type of ordinary form which they replace. The increase in circumference is to provide for additional printing spaces on the four lower order carriers. In the case 60 of the two higher order carriers, the ones for

hundreds and thousands of dollars, no change has been made except increasing their circumferences to make them conform in size to the lower order carriers, and, of course, the substitution of word printing type for the digit type.

The tens of cents and tens of dollars carriers have the same general arrangement of type as the thousands and hundreds of dollars carriers, except that they are provided 75 with one additional printing face, while the units of cents and units of dollars type carriers, in addition to the words substituted for the usual digits, have alternating therewith the words "Eleven", "Twelve" and so 80 on, and after each of the words on the units carriers is the words "Dollars" or "Cents" to designate the denominational values of words preceding in the printing line. The arrangement of the type on all of the carriers is fully shown by the chart in Fig. 3.

The improvement consists in the mechanism whereby on a registration involving the printing of amounts from eleven to nineteen inclusive, either dollars or cents, the 90 type carriers will first be positioned in the usual way by the differential mechanism, and the units and tens carriers on which such an amount has been set up will then be given a movement beyond that imparted by 95 the differential mechanism. This extra movement is for convenience usually spoken of herein as a half step of movement because its extent is about half that of a step of movement imparted by the differential mech-

anism. The additional movement of the carriers will carry away from the printing line the word on the tens carrier which was just positioned there by the differential mechanism and position in place thereof 100 type on the additional printing face above mentioned arranged to print a line of dashes.

At the same time there will be substituted for the words set up on the units type carriers, the adjacent words which properly 110 represent the value registered. For example: If a registration involves the operation of the ten and five cents keys, the units and tens of cents type carriers will be positioned by their differential devices to print the words "Ten" "Five cents". Just before the impression is taken, devices driven independently of the differential mechanism, but controlled thereby, give each of the two type carriers the additional or half step of move-

ment. This carries the word "Ten" away from the printing line and presents in place thereof the adjacent printing face which, as before stated, is provided with type to print a line of dashes. The half step of movement of the cents carriers carries the words "Five cents" away from the printing line, and substitutes therefor the adjacent words "Fifteen cents". The impression then taken 120 will be "Fifteen cents".

125 130

Operating mechanism.

The illustrative machine is, as is well known, of the two motion type; that is, one in which entries are made by first depressing the proper keys on the keyboard and then turning the operating handle. Such a machine can have any number of banks, depending upon the registering capacity desired. The invention has been shown as designed for a machine having six banks, one of which is shown in detail in Fig. 1. The remaining banks have been omitted for the sake of simplification as they are mere duplicates of the one shown. Each of the banks has a vertical row of selectively depressible keys 20 ranging in value from one at the bottom to 9 at the top. The keys are held in depressed position when operated until near the end of an operation of the main operating mechanism by a detent 21, (Fig. 1) and a retaining bar 22, with one end of the depressed key projecting into the path of a trip 23 carried by an operating member 24.

The operating handle 25 (Fig. 2) has attached thereto a pinion 26, meshing with a large intermediate gear 27 rotatably mounted on a stud shaft 28 in the machine frame. The intermediate gear, in turn, drives gears 31 and 32 attached to the shafts 33 and 34 respectively, which extend across the machine. This gearing is so proportioned that two complete rotations of the operating handle will cause the shafts 33 and 34 to be given one complete rotation.

Differential mechanism.

Running transversely through the machine is a rock shaft 35 (Fig. 1). Attached to this rock shaft is an arm 37 connected by a link 38 to an arm 39, fastened to the driving shaft 34. When the shaft 34 is rotated, the arm 39 is, of course, carried with it, thereby, through the link 38 and arm 37, rocking the shaft 35 through an arc of about 90 degrees, first clockwise and then anti-clockwise, Fig. 1. During the anti-clockwise movement, a plunger 41 carried by the operating member 24 engages a lug 42 on a plate 43 attached to a plate 36 fast on the shaft 35 and through the connection so formed the operating member 24 is carried upward during the clockwise oscillation of the plate 36 until the trip 23, which is operatively connected to the plunger 41, strikes the inner end of the depressed key and causes the plunger to be disengaged from the lug 42, thereby disengaging the connection between the operating member 24 and the plate 36. As the plunger 41 is disengaged from the lug 42 it is projected into the one of the notches 44 corresponding to the key so as to hold the operating member in its adjusted position.

The operating member 24 is formed with

a rack in mesh at all times with an intermediate gear 45, and the differential adjustment of the operating member is transmitted through said gear and a pinion 451 to an indicator 46.

70

Type carrier operating mechanism.

Extending across the machine is a shaft 47 and a series of nested sleeves 48 concentric to and supported by said shaft. Attached to the shaft and each of the sleeves is an arm 51 having a curved slot 52 co-operating with a stud 55 on the operating member 24. Through this connection the differential movement of the operating members 24 is transmitted to the shaft 47 and sleeves 48. At their right ends this shaft and sleeves each carries a rack plate 56, Figs. 2 and 5. Teeth 54 carried by these plates are at all times in engagement with gears 57 attached to the inner ends of a shaft 59 and sleeves 60. Secured to the other ends of said shaft and sleeves are type carriers 58. The mechanism just described is so proportioned that for each step of movement 90 permitted to an operating member 24 by the keys 20 the corresponding type carrier is turned one division, thereby positioning, opposite a platen 61, the type corresponding to the key 20 which was depressed at the 95 beginning of the operation.

80

85

90

95

All of the mechanism described so far is more fully shown and explained in the Carroll patent above mentioned, and reference may be had to said Patent No. 754,049, if 100 more detailed information is desired.

As hereinbefore stated, the units and tens type carriers of both the dollars and cents denominations are on certain registrations given a half step of movement by devices 105 driven independently of, but controlled by the differential mechanism. The means whereby this is accomplished comprises disks 62 attached to the sides of the type carriers, as best shown in Fig. 4. The disks for the 110 units of cents and units of dollars are each provided with 10 lugs 63, while the disks attached to the tens of cents and tens of dollars carriers each have but a single lug 631. No lugs are provided for the hundreds and 115 thousands of dollars carriers because they are positioned entirely by the differential mechanism, that is to say, they are never given the half step of movement which is at certain times imparted to the four lower order carriers.

120

Arranged to act against the lugs 63 and 631 at the proper times are slides 64, Figs. 2 and 5, one for each of the four lower order carriers. These slides are held 125 against lateral displacement by a slotted guide 65 supported by the printer frames, and are pivoted at their rear ends to arms 66 secured to a rock shaft 67. Fastened to said rock shaft is a short rearwardly ex- 130

tending arm 68, to which is pivoted one end of a pitman 69 slotted to encompass the shaft 34 and carrying at its upper end a roller 71 projecting into a cam groove 72 formed in the side of the gear 32. It will be remembered that this gear makes a complete rotation on every operation of the machine. The configuration of the cam groove is such, that near the end of the operation 10 of the shaft 34 the shaft 67 is rocked, and the slides 64 are first thrown forward and then returned to the normal positions in which they are shown in the drawings. It is during this forward movement, if at all, 15 that these slides engage the lugs 63 and 631 attached to the type carriers to give the carriers the half step of movement above mentioned. However, this result is normally prevented by the forward ends of the 20 slides being held up so that during their reciprocation they pass above the lugs 63 and 631, thereby causing the movements of the slides to be idle ones. The slides are held up in this ineffective position by arms 25 75 pivoted on the shaft 67, and carrying at their forward ends rollers 76 extending into slots 77 formed near the lower edge of the slides 64. The arms are in turn supported by rotatable elements driven by the differential mechanism, and so shaped that when 30 they are driven to certain positions, they allow the arms 75 and slides 64 to be drawn down by springs 78, so that when the slides are given the usual reciprocation their ends 35 will engage such lugs 63 and 631 as may happen to be in their paths and rotate the corresponding type carriers. The extent of the reciprocation of the slides 64 is just sufficient to rotate the carriers half the distance that they are rotated by a step of the differential mechanism.

The devices employed whereby the slides 40 64 are lowered at certain operations will next be described. The plates 56 (Fig. 2) carrying the racks for positioning the four lower order type carriers have integral therewith racks 81, which are constantly in engagement with gears 82 (Figs. 5 and 6). The left hand one of these gears is attached to a shaft 83 rotatably mounted in the printer frames. This gear and shaft are driven by the differential mechanism for the lowest order or units of cents bank. Concentric to and supported by 45 the shaft 83 are three sleeves 84, each having attached to its left end one of the gears 82. These gears are driven by the differential mechanism of the tens of cents, units of dollars and tens of dollars banks 50 respectively from left to right in the order named.

Fastened to the right hand end of the shaft 83 is a gear 91 meshing with a gear 92 secured to a short shaft 93, journaled at 55 one end in the outside printer frame, and

at the other in a boss carried by the upper end of a bracket 931 (Fig. 5) attached to said frame. Rigid on the shaft 93 is a second gear 94 (Fig. 6) meshing with a gear 95, rotating on the tens of cents sleeve 84. 70 Secured to the gear 95 so as to rotate therewith is a disk 96 having an ear 97, best shown in Fig. 7, which in the normal or zero position of the units of cents differential mechanism rests under a roller 98 carried by the arm 75 for the tens of cents bank, and holds said arm and its slide 64 in the raised position. The ear 97 is so shaped that if the shaft 83 is rotated even a single step by the units of cents differential mechanism, the slide 64 will be lowered and will engage the lug 631 associated with the tens of cents type carrier if said lug is at the time in the path of the slide. It should be pointed out here, however, that 85 the tens of cents type carrier has but the one lug and this is only in the path of the corresponding slide 64 when said carrier has been rotated but a single division. When the carrier is at the zero position the lug 90 rests too far to the rear to be engaged by the slide and, on the other hand, if the carrier is rotated more than one step the lug 95 631 is carried so far that it is out of the path of the end of the slide.

The tens of cents sleeve 84 which, as already indicated, is the one next to the shaft 83, carries at its right end a disk 101 (Figs. 6 and 7) having a notch 102 in its periphery. A single step adjustment of the dimes bank differential mechanism, such as occurs when the machine is operated with the ten cent key depressed, will cause the disk 101 to be rotated one step from the zero position in which it is shown, bringing the 100 notch 102 under the roller 98 carried by the arm 75 for the units of cents bank. This allows said arm and the connected slide 64 to be lowered by the corresponding spring 78 so that when the slide is reciprocated its 105 forward end will engage whichever one of the ten lugs 63 carried by the units of cents type carriers happens to be in the path of the slide 64 and rotate the carrier a half step beyond the position to which it was 110 previously adjusted by its differential mechanism. In all positions of the tens of cents differential mechanism other than the one just mentioned, the units slide is held in ineffective position by the periphery of the 115 disk 101.

As an illustration of the way this controlling mechanism works, take the fifteen cent registration above mentioned. The dimes type carrier and the disk 101 are rotated a 120 single step by the tens of cents differential devices, thereby bringing the notch 102 in said disk under the roller 98 and allowing the arm 75 for the units of cents bank and the slide 64 connected thereto to be drawn 125 130

down to effective position. At the same time, the differential mechanism for the units of cents bank will position its type carrier and rotate the shaft 83, gears 91 and 92, the short shaft 93, the gears 94 and 95 and the disk 96, five steps. At the beginning of this rotation, the ear 97 on the disk 96 is carried from under the roller 98 on the arm 75 for the dimes bank, allowing the arm 10 and corresponding slide 64 to be lowered. As the one step of rotation of the tens of dimes carrier has carried the lug 631 into the path of the slide 64, when the slide for that bank is reciprocated said lug will be engaged 15 and the tens type carrier moved forward a half step. This will bring the space between the words "Ten" and "Twenty", see Fig. 3, to the printing line. This space is arranged to print a series of dashes to fill 20 up the space which would otherwise be left blank. During its reciprocation the slide for the units of cents bank will engage the one of the lugs 63 which was brought into effective position by the five steps of rotation 25 of the units of cents type carrier and give the units carrier a half step of movement, carrying the words "Five cents" away from the printing line and presenting in place thereof the adjacent words "Fifteen 30 cents".

From the immediately preceding description it is apparent that if the ten cent key only is pressed, the disk 101 will be rotated the right distance to present its notch 102 to the roller 98 for the units of cents bank, thereby allowing the arm 75 and slide 64 for that bank to be lowered. In such a registration the units of cents type carrier will be set at its normal zero position, in which 40 position it prints the characters "Cents —", but these type are carried away from the printing line in the usual way by the operation of the slide 64. In order to take care of the condition just mentioned; that 45 is, to properly print in the units division when the ten cent key only is operated, the designation for the zero position is repeated at the next half step above on the type carrier so that when the slide 64 operates, 50 the half step of movement imparted to the carrier will cause it to print the same character as though the carrier remained undisturbed in its zero position. It is obvious, however, that the lug 63 at the zero position 55 might be omitted instead of duplicating the type for the zero position.

The mechanism for imparting the half step of movement to the units and tens of dollars type carriers is the same as the 60 mechanism for the units and tens of cents carriers, just described. Inspection of Figs. 6 and 8 will show this. The two outer tubes 84 carry disks, which are the same as those already described in detail, and the 65 parts are all operated in the same way to

produce like results. There is, therefore, no necessity for repeating the description.

In the foregoing, reference has been made to the fact that the four lower type carriers are capable of a half step of movement independent of the differential mechanism. The devices by which this independent movement of the carriers is permitted are shown in Fig. 8. Each of these four carriers is hollow and has an internal hub 111, 75 loosely journaled on the shaft 59 or one of the tubes 60 as the case may be. A rib 112 extends between the hub and the outside shell of the carrier. Fastened to the shaft 59 and each of the tubes 60 is a disk 113 80 having a slot 114 through which extends a stud 115 on the rib 112. A spring 116 is fastened at one end to the stud 115, and at the other end to a stud 117 on the disk 113. This construction causes the type carrier to 85 move in correct relation to the movement of its differential mechanism, but when a slide 64 gives one of these carriers a half step of movement, the carrier is moved against the tension of the spring 116 until the stud 115 90 is carried to the opposite end of the slot 114 from that at which it is shown. When the slide is drawn rearward to its normal position the spring returns the carrier to 95 normal relation with its differential devices.

Inking and impression taking devices.

An inspection of the cam groove 72 formed in the gear 32 on shaft 34 (Fig. 2) will show that after it operates the pitman 100 69 to throw the slides 64 forward, it holds the pitman and slides in their operated positions for some little time. If the slides have been lowered and engage the lugs on the type carriers, the carriers are during this 105 time held in their half step positions of adjustment against the tension of their springs 116. However, regardless of whether or not any of the carriers are at the time being so held in their half step positions, it 110 is during this period of the operation that the position type are inked and impression taken therefrom.

The ink for the type is supplied by a pad 121 carried by a plate 122 supported at 115 either end so as to have a slight rocking movement by studs 123 on arms carried by rotatable elements 120. The right hand one of these elements is journaled on the shaft 59 while the other rotates about the outer 120 type wheel sleeve 60, see Fig. 5. Rigid with the elements 120 are other elements 118 bearing teeth 119. For each of these toothed elements there is provided a pitman 125 (Figs. 2 and 5). These pitmen have elongated openings at their forward ends surrounding the toothed elements 118 and are provided with teeth 124 meshing with the teeth 119. At their rear ends the pitmen are slotted to straddle a shaft 126 and each 130

carries an antifriction roller 127 projecting into a cam groove 128 formed in the sides of gears 129 secured to the shaft 126. The gears 129 are in mesh with gears 130 secured to a shaft 131 journaled in the printer frames and these gears 130 are in turn, in mesh with gears 132 attached to the driving shaft 34. As before stated, the shaft 34 makes one complete rotation at each operation of the machine and the gears 129 and 130 are rotated to the same extent. The configuration of the cam grooves 128 is such that at near the end of an operation of the machine the pitmen 125 are thrust forward and the teeth 124 acting against the teeth 119 cause the elements 120 to be rotated to bring the ink pad 121 over the platen 61.

The platen 61 is raised twice during each operation. The first time it presses the ink pad against the type carriers, after which the pad is restored to the normal position in which it is shown in Fig. 2, and the second time it presses the inserted paper against the type to take the impression from the type of the item set up thereon.

The platen 61 is adjustably mounted in a frame 135 arranged to slide vertically in a bracket 136 secured to the machine frame. At each end of the frame 135 is a stud 139 projecting through a slot in the forward end of one of a pair of levers 137. The levers 137 are pivoted on a rod 138, and at their rear ends carry anti-friction rollers projecting laterally into cam grooves 141 formed in the sides of gears 142 secured to a short shaft 143 journaled in the printer frame. These gears are, through the gears 132 and 129 rotated once at each operation of the machine. As shown the cam grooves 141 are arranged to operate the levers 137 twice at each rotation of the gears 142, raising the platen a corresponding number of times. As already indicated at the first operation the ink pad is pressed up against the type, and at the next the check or other record material is pressed against the face of the type.

Attached to the machine frame is a table 144 to receive the check or other paper on which the amount is to be printed. This table extends the width of the type carriers, and has an opening through which the platen 61 operates. A stop 145, which of course may be arranged to be adjustable to different positions, serves as a guide in placing the paper on the table to insure positioning the paper correctly to effect the printing at the desired point.

60 Operation.

In describing the mechanism, it has been necessary incidentally to explain the operation of the devices comprised by the improvement to such an extent that it is

thought that only a very brief summary of 65 the operation is necessary here. The check or other paper which is to receive the impression is laid upon the table 144 with its upper edge against the stop 145. The proper keys are then depressed to set up on the 70 keyboard the amount which is to be printed, and the handle 25 turned. The differential mechanism controlled by the keys and driven from the operating handle rotates the type carriers 58 in the usual manner to position opposite the platen 61 the words on each representing the different keys pressed. If the amount to be printed does not include any of the numbers 11 to 19 inclusive in either the dollars or cents orders, the impression is simply taken from the positioned 75 type carriers in the usual way. If, however, the amount to be printed does involve the printing of one of such amounts, both the units and tens type carriers of the denominational orders involved are given a half 80 step of movement in addition to the movement just imparted by the differential mechanism. This half step of movement carries away from the printing line the word Ten 85 on the higher order carrier which was positioned at the printing line, and substitutes therefor type faces arranged to print simply a line of dashes or other characters to fill up the space which would otherwise be 90 left blank. The half step of movement of the units type carrier moves away from the printing line the words which were positioned at the printing line by the differential mechanism and substitutes therefor words 95 on said carrier indicating the total value represented by the two keys operated in the units and tens banks. For example, in a fifteen cent registration the differential mechanism would operate the type carriers 100 to position at the printing line the word "Ten" on the tens type carrier and the words "Five cents" on the units type carrier. The controlling disks 96 and 101 would incidentally be operated by the differential mechanism to allow the corresponding slides 64 to be lowered so that when said slides are reciprocated the lugs 631 on the tens type carriers and the proper lug 63 on the units carrier would be engaged, thereby rotating 105 the two carriers a half step beyond the positions to which they were adjusted by their differential devices. This substitutes for the word "Ten", the type to print the row of dashes, and for the words "Five cents" the words "Fifteen cents". The type are then inked and the impression taken while the auxiliary devices hold the carriers in their 110 newly adjusted positions, and upon the withdrawal of the auxiliary devices, the type carriers are returned to their normal relations to the differential mechanism. 115 It is to be understood that while the in-

vention has been shown as applied to a machine of the type illustrated, the vital parts thereof are obviously applicable to devices employing other forms of differential mechanism or capable of use with merely a simple form of adjusting means for the type carriers.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:—

1. In a machine of the class described, the combination with a series of non-accumulating accounting elements, of devices for individually and differentially operating said elements, and means controlled by said devices for giving the elements a degree of movement separate from the movements imparted by the differential devices.

2. In a machine of the class described, the combination with a series of differentially movable non-accumulating accounting elements, of devices for differentially moving said elements, and means associated with certain of the elements and controlled by the differential devices for giving the elements movement relative to the differential devices.

3. In a machine of the class described, the combination with a series of differentially movable non-accumulating printing elements, of devices for differentially operating said elements, and means associated with certain of said movable elements and controlled by the operating devices therefor for giving said certain elements movement beyond that imparted to them by their operating devices.

4. In a machine of the class described, the combination with non-accumulating type carriers, of devices for setting up items thereon, and means associated with two adjacent carriers and controlled by the setting up devices therefor for giving one or both of said carriers a movement separate from the movement imparted by the setting up devices.

5. In a machine of the class described, the combination with a series of differentially operable non-accumulating printing elements, of manipulative devices, means controlled by said devices for differentially operating the aforesaid elements, and means also controlled by said devices for causing movement of certain elements relative to the differential means.

6. In a machine of the class described, the combination with a plurality of differ-

tially operable non-accumulating printing elements, of manipulative devices, means controlled by said devices for differentially operating the aforesaid elements, means also controlled by said devices for causing movement of certain elements relative to the differential means, and means for reestablishing normal relationship between the elements and the differential means after the purpose of the relative movement has been accomplished.

7. In a machine of the class described, the combination with non-accumulating type carriers, of key controlled differential devices for operating said carriers, an invariably moved driving mechanism for operating the differential mechanism, and means given an invariable movement by the driving mechanism and controlled by the differential devices for giving certain carriers movement beyond that imparted by the aforesaid operating means.

8. In a machine of the class described, the combination with non accumulating printing elements and means for individually and differentially operating the same, of means associated with two adjacent printing elements and controlled by the operating means therefor to give the lower order element or both the lower and the higher order element a degree of movement separate from that imparted by the aforesaid operating means.

9. In a machine of the class described, the combination with non-accumulating type carriers, of devices for setting up items thereon, normally ineffective means associated with each of two adjacent carriers for imparting movement to said carriers in addition to the movement by the setting up devices, and means controlled by the setting up devices for each carrier for rendering the first mentioned means associated with the other carrier effective to move said other carrier.

10. In a machine of the class described, the combination with a plurality of banks of keys, of a main operating mechanism, devices differentially adjusted under the control of the keys by operations of the operating mechanism, non-accumulating elements bearing characters representing the keys and rotatable by the differential devices to bring the characters representing the keys used to the position where such characters perform their function, and means controlled by adjacent key banks for giving one or both of the associated rotatable elements movement relative to their differential devices to bring other characters to the functioning position.

11. In a machine of the class described, the combination with non-accumulating type carriers, of differential devices for operating same, manipulative devices for controlling the differential devices, and means associated

- with two adjacent type carriers and controlled by the manipulative devices for giving one or both of said carriers movement separate from the movement imparted by the differential devices.
12. In a machine of the class described, the combination of non-accumulating indicating mechanism of different orders, differential mechanism for setting up the same, 10 and a transfer mechanism from one order to another controlled by the differential mechanism independently of the indicating mechanism.
13. In a machine of the class described, 15 the combination with differentially adjustable item printing type carriers, of differential mechanism for adjusting said type carriers, normally ineffective means for giving the type carriers movement relative to the differential mechanism preparatory to printing certain items, and devices adjusted by the differential mechanism for rendering said means effective when such items are to be printed.
14. In a machine of the class described, 20 the combination with two non-accumulating type carriers, of differential devices for operating each of the carriers, manipulative means for controlling the movement of the differential devices, and means controlled by the manipulative means for imparting movement to the type carriers independent of the differential devices whereby to give an erasing movement to the higher order 25 carrier and set up on the lower order carrier characters representing the amount previously set up on the two type carriers by the differential devices.
15. In a machine of the class described, 30 the combination with non-accumulating type carriers, of devices for individually and differentially positioning same, a series of keys for each carrier controlling the positioning devices therefor, and devices associated with 35 two adjacent carriers and controlled by the keys therefor whereby the higher order carrier may be given an erasing movement and the lower order carrier a setting up movement to position characters thereon representing keys in both the higher and lower order series, said erasing and setting up 40 movements being in addition to movements imparted by the aforesaid differential devices.
16. In a machine of the class described, 45 the combination with a plurality of non-accumulating type carriers, of differential devices for operating said carriers, a plurality of elements normally ineffective but having an invariable extent of movement, and means controlled by the differential devices for rendering the invariably moved elements effective to give their type carriers movement separate from the movement imparted 50 by their differential devices.
17. In a machine of the class described, the combination with a plurality of non-accumulating type carriers, of devices for differentially operating same, an auxiliary operating means associated with adjacent type 55 carriers and controlled by their differential devices for giving said carriers movement separate from the movement imparted by the differential devices, and means permitting such movement of the carriers independently of the differential devices.
18. In a machine of the class described, 60 the combination with a plurality of type carriers, of a series of keys for each type carrier, differential devices for operating the carriers and controlled by the respective series of keys to position characters representing keys depressed, and means whereby operation of a certain key in one series and any key in the adjacent series will render 65 the one carrier ineffective to print the designation for said certain key and the other carrier effective to print characters representing both of the keys operated.
19. In a machine of the class described, 70 the combination with a main operating mechanism, of a plurality of type carriers, a series of keys for each type carrier, differential devices driven by the operating mechanism and controlled by the keys to 75 position the type on the carriers designating the keys operated, and means given an invariable movement by the operating mechanism and controlled by the keys of adjacent banks for giving one type carrier an erasing 80 movement and the other a setting up movement to position type arranged to print a designation for the keys in both banks, said erasing and setting up movements being 85 separate from the movements imparted by the differential mechanism.
20. In a machine of the class described, 90 the combination with a plurality of type carriers, of differential devices permanently connected to the type carriers and arranged to differentially position said carriers, devices associated with adjacent type carriers and controlled by the differential devices for creating relative movement between the type carriers and the differential devices, 95 and means intermediate the type carriers and the differential devices both permitting said relative movement and operating to re-establish normal relationship between the carriers and the differential devices when 100 the purpose of the relative movement has been accomplished.
21. In a machine of the class described, 110 the combination with differential operating mechanism and auxiliary operating mechanism, of type carriers having a plurality of printing faces and arranged to be operated by said mechanisms whereby certain of the printing faces may be selectively adjusted to effective position by operations of the dif- 115

- ferential mechanism only or others by combined operations of the differential mechanism and the auxiliary mechanism, and a keyboard controlling said mechanisms.
- 5 22. In a machine of the class described, the combination with a type carrier for printing words representing digits and single words representing the numerals 11 to 19 inclusive, of a type carrier for printing 60 the tens in words, means for operating the type carriers, and auxiliary means for automatically operating said type carriers to print "eleven", "twelve" and the teens instead of "ten" and the digits.
- 10 23. In a machine of the class described, the combination with a type carrier for printing words representing digits and single words representing the numerals 11 to 19 inclusive, of a type carrier for printing 70 the tens in words, means for operating the type carriers differentially and then automatically giving both type carriers extra movements if "ten" and a digit are moved to the printing line so that only "eleven", "twelve" and the teens are printed automatically from the first type carrier instead of 75 "ten" and the digits from both operated type carriers.
- 15 24. In a machine of the class described, the combination with a type carrier having words representing digits, and single words representing the numerals 11 to 19 inclusive alternately arranged thereon, of a type carrier having words representing tens, means for operating the type carriers, and auxiliary means for moving both type carriers an extra step if "ten" and a digit are brought to the printing line so that only "eleven", "twelve" or a teen is finally positioned at the printing line.
- 20 25. In a machine of the class described, the combination with a type carrier having words representing digits and single words representing the numerals 11 to 19 inclusive alternately arranged thereon, of a type carrier having words representing tens, means for operating the type carriers, and auxiliary means for moving both type carriers an extra step if "ten" and a digit are brought to the printing line so that only "eleven", "twelve" or a teen is finally positioned at the printing line.
- 25 26. In a machine of the class described, the combination with a type carrier having words representing digits and single words representing the numerals 11 to 19 inclusive alternately arranged thereon, of a type carrier having words representing tens, differential means for operating the type carriers, and auxiliary means for moving both type carriers an extra step relative to the differential means if "ten" and a digit are brought to the printing line, so that only "eleven", "twelve" or a teen is finally positioned at the printing line.
- 30 27. In a machine of the class described, the combination with a printing mechanism comprising impression means, operating means therefor, a type carrier having words representing digits and single words representing the numerals 11 to 19 inclusive, a type carrier having words representing the tens and operating means for the type carriers; and so constructed that the "eleven", "twelve" and the teens are printed automatically from the first type carrier instead of 80 "ten" and the digits from both operated type carriers.
- 35 28. In a machine of the class described, the combination with impression means, of a type carrier having words representing digits and single words representing the numerals 11 to 19 inclusive, a type carrier having words representing the tens, differential mechanism for operating the type carriers, and means automatically controlled 85 in accordance to the positions of the type carriers and so constructed that "eleven", "twelve" and the teens are printed from the latter instead of "ten" and the digits.
- 40 29. In a machine of the class described, the combination with differential operating mechanism and auxiliary operating mechanism controlled by the differential operating mechanism, of type carriers having a plurality of printing faces and arranged to be 90 operated by said mechanisms whereby certain of the printing faces may be selectively adjusted to effective position by operations of the differential mechanism only or others by combined operations of the differential 95 mechanism and the auxiliary mechanism, and a keyboard controlling said mechanisms.
- 45 30. In testimony whereof I affix my signature in the presence of two witnesses.

EDWARD J. VON PEIN.
